UNITED STATES PATENT OFFICE

CARL G. MILLER, OF MOUNT CLEMENS, MICHIGAN

FURNACE

Application filed April 4, 1928. Serial No. 267,156.

This invention relates to a furnace, and has to do more particularly with a furnace of the type which effects heating by the heating of air and the setting up of convection currents. The invention can be embodied in a hot air furnace commonly placed in the basement of a residence with the hot air conducted through pipes to the rooms to be heated, or the invention can be embodied in a so-called parlor furnace or stove.

The invention has as an object the provision of a heater of the type mentioned which is constructed so as to accelerate the heating action, especially when there is a newly built fire or the intensity of the fire increased. The slowness of the heating effect in furnaces of this nature is particularly noticeable where the furnace is in the basement as it takes quite a while before the convection currents start moving to any appreciable extent. Also the invention aims to provide a furnace simple in construction and which can be easily cleaned of soot, and for this purpose the construction contemplates a simple arrangement which functions both to speed up initial heating action and to collect soot.

More specifically, the invention contemplates the use of tubes in close proximity to the fire box. These tubes are for the purpose of the passage of air therethrough so that convection currents are set up. It is appreciated that the use of air tubes of this nature is not new, and in fact are shown in a number of patents, but the present invention makes use of additional elements which in combination with the tubes, obtains new and better results.

In the accompanying drawings:

Fig. 1 is a sectional view taken through the furnace, the section being taken from the front to the rear of the furnace substantially on line 1—1 of Fig. 2.

Fig. 2 is a sectional view taken substantially on line 2—2 of Fig. 1.

Fig. 3 is a horizontal section on line 3—3 of Fig. 2 illustrating the manner in which the soot collecting member may be removed.

Fig. 4 is a fragmentary front view of the furnace.

Fig. 5 is a detail of a modified manner in which the air tubes can be mounted in the furnace.

The furnace includes an outer shell 1 having a cold air inlet 2, and may be provided with a plurality of hot air outlets to which conduits may be attached for conducting the hot air to rooms to be heated. The cold air inlet may be connected to the outside of the building, or it may take air from the lower part of the rooms to which the hot air is conducted thus setting up a circulation of air. The drawings depict the invention as embodied in the type of furnace usually placed in a basement, but the principles of the invention described below can be equally well embodied in the so-called parlor furnace without deviating from the invention.

Within the outer shell is a heating unit 5 spaced from the outer shell so as to provide an air heating space 4, this being the customary air heating space of the hot air furnace. The heater unit includes the fire box 6 to which access may be had through a fuel feed door 7. A suitable grate 8 is provided, below which is an ash pot 9. A suitable draft door is represented at 10, and at 11 there is a pivoted enclosure for an opening through which a tool can be inserted for shaking the grate. It will be noted that the walls of the fire box, as illustrated in Figs. 1 and 2, practically meet the edges of the grate without the interposition of a shoulder or ring. This construction materially facilitates the shaking of ashes out of the fire box inasmuch as there is no ledge or shoulder around the edges of the fire box where clinkers or the like may collect.

Above the fire box, the inner heating unit is provided with a drum 15 within which are confined the flame of the fire and products of combustion, and this drum may advantageously be of boiler iron or sheet steel. As will be noted, the drum is larger than the fire box. Extending vertically through the drum and positioned around the fire box are a plurality of pipes 16 which are open at both the lower and upper ends. The lower ends preferably extend down below the drum and in fairly close proximity to the bottom of the furnace. These pipes can be placed

in the drum in any desirable manner, and one way consists of providing on the pipes a shoulder 17, which may be a ring clamped thereto, and then screw threading a ring 18 at the upper end. By screwing the rings down tight the drum ends are clamped between the two rings and smoke-tight joints are effected. Suitable gaskets of an asbestos composition or the like can be used if desired. Another manner of securing the pipes to the drum is shown in Fig. 5 wherein it will be noted that the upper ends of the pipes are riveted over as at 19.

The top of the drum is provided with a suitable smoke hood 20 leading to smoke pipe 21. For the purpose of maintaining a proper relative humidity of the heated air, a water pipe 22 may extend through the casing 1 and arrange to drip water into the pan 23 fixed to the top of the smoke hood.

At a point near the upper ends of the air pipes and above the fire box, there is placed a deflector for the products of combustion, and this deflector also functions to collect soot. This deflector may take the form of a metal plate 25, and for the purpose of supporting this plate, a pair of rods 26 may be placed across the drum. Attention is called to the fact that this plate is of such a size as to nicely fit in between the air pipes so that the products of combustion coming up from the fire box are deflected by the plate and caused to flow outwardly in three directions in contact with the air pipes near the upper ends thereof. In other words, viewing Fig. 2, the products of combustion are deflected outwardly into the space 27 surrounding the air pipes, whereupon the products of combustion return back over the plate 25 before entering the smoke pipe.

Thus it will be seen that the products of combustion are caused to come into contact with the upper ends of the pipes so that the air at this point is subjected to intensive heat. The air at the bottom of the pipes, however, is not subjected to such a degree of heat and accordingly remains cooler. As a result, there is practically an immediate movement of the air through the tubes. This is especially true when the fire is built or when a low fire is increased in intensity.

Another important feature is the fact that the products of combustion pass outwardly around the sides of the deflector plate and then inwardly above the deflector plate. The speed of movement above the deflector plate is diminished somewhat, and also there is a change in the direction of movement, and this results in a material deposit of soot on the deflector plate. For the purpose of cleaning the furnace, a clean-out door is provided immediately at the front of this deflector plate. When the door is open, as illustrated in Fig. 4, the soot can be raked out the of the door opening with a suitable tool; or, on the

other hand, the plate may be removed entirely by being drawn forwardly through the door opening, as illustrated in Fig. 3, and the soot can be removed after the plate is removed, whereupon it can be inserted again in the furnace.

It is thought that the air tubes should be protected near the fire box so that they will not be damaged if lumps of coal are thrown into the furnace and strike the pipes, or if the fire in the fire box is permitted to pile up above the fire box. For this purpose a ring of iron or steel 31 may be placed around each pipe in the position as shown in Figs. 1 and 2. These rings may be merely loosely placed on the pipes and allowed to rest upon the lower end of the drum.

In the claims appended hereto, reference is made to a furnace; this is done for the purpose of brevity, and it is to be understood that this term is used with the intention that it be construed to cover heaters other than furnaces, for example, stoves or parlor type heaters.

Claims:

1. A hot air furnace or the like comprising, an outer shell, an inner heating unit spaced from the outer shell to provide an air heating space, said heating unit including a fire box and a drum above the fire box, said drum having horizontal dimensions greater than the fire box, a plurality of tubes extending vertically through the ends of the drum so as to surround the fire box, said tubes extending downwardly into close proximity of the bottom of the air heating space, and communicating with the said air heating space above the drum, means within the drum for deflecting the products of combustion to the ends of the drum between the said air pipes, said means being positioned near the upper end of the drum whereby the upper ends of the said pipes are relatively quickly heated to thus set up, practically immediately, air convection currents, and means at the top of the outer shell for conducting the convection currents for heating purposes, said deflector being in the form of a plate removably held within the heater unit, and the furnace being provided with an opening in substantial alignment therewith whereby the plate may be removed for the removal of soot therefrom.

2. A hot air furnace comprising, an outer shell, a fire box, a drum positioned above the fire box, said drum having horizontal dimensions greater than the fire box, a plurality of vertically disposed air conduits extending through the drum, a smoke hood connected substantially centrally with the top of the drum, a combined baffle member and soot collector disposed between the fire box and the smoke hood, said member having dimensions so as to substantially fit the area bounded by the vertical air conduits, whereby the

products of combustion are caused to pass to the outer walls of the drum between the spaced air conduits and back between the spaced conduits over the baffle member to the smoke hood, means for removably supporting the baffle member, and a closure in the outer shell through which the said member may be withdrawn for cleaning purposes.

3. A hot air furnace comprising, an outer shell, a fire box, a drum positioned above the fire box, said drum having horizontal dimensions greater than the fire box, a plurality of vertically disposed air conduits extending through the drum, a smoke hood connected substantially centrally with the top of the drum, a combined baffle member and soot collector disposed between the fire box and the smoke hood, said member having dimensions so as to substantially fit the area bounded by the vertical air conduits, whereby the products of combustion are caused to pass to the outer walls of the drum between the spaced air conduits and back between the spaced conduits over the baffle member to the smoke hood, a pair of rods extending across the drum for slidably supporting the said baffle member, and a closure in the outer shell in substantially vertical alignment with the rods through which the said baffle member may be withdrawn.

In testimony whereof I affix my signature.
CARL G. MILLER.
